UNITED STATES PATENT OFFICE

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY

STEAM BOILER

Application filed May 13, 1925. Serial No. 29,906.

My invention more particularly relates to an arrangement for preventing priming in a boiler.

My invention will best be understood by reference to the accompanying drawings in which I have illustrated one embodiment of my invention, and in which Fig. 1 is a fragmentary section through a steam boiler of the general Stirling type embodying my invention, Fig. 2 is a sectional view illustrating a modification wherein the vessel is applied to the rear steam and water drum, and Fig. 3 is a vertical sectional view through a boiler showing the lower drum.

The boiler illustrated comprises a plurality of upper transverse steam and water drums, here shown as three in number, and including a front drum 10, a middle drum 11 and a rear drum 12. The upper steam and water drums are connected by respective banks of tubes 13, 14 and 15 to a lower mud drum 26. The front drum is connected to the middle drum by water circulators 16 and steam circulators 17, while the middle drum 11 is connected by steam circulators 18 to the rear drum 12. Certain tubes 15' in the bank 15 are connected at their upper ends to the middle drum 11, thus forming a connection through the tubes and mud drum between the drums 11 and 12. The drums 10, 11 and 12 are therefore connected both above and below the normal water line so that pressure may be approximately equalized.

In the illustrated embodiment of my invention, the means for preventing priming in the boiler comprises a vessel 19 located in one of the upper steam and water drums and preferably within the middle drum below the steam outlet connections to the circulators 18. The vessel 19 is preferably open at its top and with the upper edge preferably substantially horizontal, the vessel being located at the highest desired water level in the drum 11. The vessel 19 is supported from the drum by a suitable number of brackets 20 extending to the drum, one edge of the vessel preferably being separately supported from the drum as at 21. The vessel which is preferably oblong in form extends longitudinally of the drum, and preferably extends substantially the entire length of the drum. A pipe connection 22 passes through one end of the vessel 19, the pipe extending downwardly from the drum as illustrated. A trap 23 is included in the pipe connection 22 that seals the steam and water drum 11 from the atmosphere, but through which the water is forced when a sufficient head has been produced in the pipe connection combined with the boiler pressure. The connection 22 also preferably includes a means for utilizing the heat in the water blown from the drum, and in the form illustrated, comprises a heat transfer device 23' in the form of a vessel to which the pipe 22 is connected and from which the connection 22' leads, the feed pipe 24 which leads to the rear drum 12 passing through the vessel 23' and being provided with a coil 25 located therein, in order effectively to transfer to the feed water the heat from the water blown from the drum.

It is well understood that in the operation of a boiler, over-concentration of solids in the boiler results in priming. When over-concentration occurs, the water rises in the drums. In the type of boiler shown, the front bank of tubes 13 is the one which is exposed to the hottest gases and the bank 15 is exposed to the same gases after they have become cooled. Any intermediate banks such as the bank 14, are subjected to the gases at an intermediate stage, as regards their temperature. The result is that the densest water is in the bank 15 and in the steam and water drum 12 and the water in the banks 14 and 13 is progressively less dense as is well known in the art. Therefore, the level of water in the front drum is higher than in the middle and rear drums and that in the middle drum is higher than in the rear drum. If this water reaches too high a level, it will be forced over through the steam circulators into the next drum to the rear and if forced into the rear drum 12, may decrease the density of the water in that drum and in the rear bank of tubes 15 to such a degree that the water in the rear drum will rise to such an extent as to cause priming. This is particularly the case with impure water having a

high concentration. When a Stirling boiler is equipped with the described automatic blow-off device, with the vessel included in the blow-off device located in the intermediate or rear upper steam and water drum, then when the water, because of the concentration and the resulting rise in level, reaches the top of the vessel 19, water is automatically blown from the vessel and from the drum, thereby preventing the water rising above the top of the vessel and, in turn, preventing over concentration of solids in the water and resulting priming.

In Fig. 2, I have illustrated a modification wherein the vessel 19 is applied to the rear steam and water drum instead of the intermediate drum as in Fig. 1, it being understood, of course, that the parts to which the pipe 22 is connected are the same as those illustrated in Fig. 1.

By the heat transfer device which I preferably provide, the heat in the water thus blown off, may be returned to the system.

While I have illustrated my invention in connection with a Stirling boiler, it will be understood that its use is not limited to this type of boiler. Furthermore, the embodiment may be widely varied.

I claim:

30 1. In a boiler, a plurality of steam and water drums, tubes connecting each of said drums to a lower water drum, connections between said drums above and below the normal water levels therein, a steam outlet on one of said drums, and means in one of the other drums to prevent the level of water in said first drum rising sufficiently to cause priming.

40 2. In a boiler, a plurality of steam and water drums, tubes connecting each of said drums to a lower water drum, connections between said drums above and below the normal water levels therein, a steam outlet on one of said drums, and means in one of said drums to prevent the level of water in said first drum rising sufficiently to cause priming.

50 3. In a boiler, a plurality of steam and water drums, tubes connecting each of said drums to a lower water drum, connections between said drums above and below the normal water levels therein, a steam outlet on one of said drums, and means preventing discharge of water from the other drums into the drum from which steam is taken.

60 4. In a boiler, a plurality of steam and water drums, tubes connecting each of said drums to a lower water drum, connections between said drums above and below the normal water levels therein, a steam outlet on one of said drums, and means for preventing priming by preventing the level of water in one of the other drums from rising beyond a certain predetermined level.

65 5. In a boiler, a plurality of steam and

water drums, tubes connecting each of said drums to a lower water drum, connections between said drums above and below the normal water levels therein, a steam outlet on one of said drums, and means for preventing priming by preventing the level of water in one of said drums from rising beyond a certain predetermined level.

70

6. In a boiler, a plurality of steam and water drums, tubes connecting each of said drums to a lower water drum, connections between said drums above and below the normal water levels therein, a steam outlet on one of said drums, and means to prevent priming by preventing substantial decrease of the density of the water in the drum having the steam outlet.

75

7. In a boiler, a pair of steam and water drums, tubes connecting each of said drums to a lower water drum, connections between said drums above and below the normal water levels therein, a steam outlet on one of said drums, and a blow-down device disposed in one of said drums and constructed and arranged to maintain the level of water therein below a predetermined high point.
